Paul A. Cuenot INVENTOR

BY *Frederick W. Bond*

ATTORNEY.

UNITED STATES PATENT OFFICE.

PAUL A. CUENOT, OF CANTON, OHIO.

RIVETING-MACHINE.

SPECIFICATION forming part of Letters Patent No. 530,162, dated December 4, 1894.

Application filed March 17, 1894. Serial No. 504,111. (No model.)

To all whom it may concern:

Be it known that I, PAUL A. CUENOT, a citizen of the United States, residing at Canton, in the county of Stark and State of Ohio, have 5 invented certain new and useful Improvements in Riveting-Machines; and I do hereby declare that the following is a full, clear, and exact description of the same, reference being had to the annexed drawings, making a part 10 of this specification, and to the letters of reference marked thereon, in which—

Figure 1, is a side elevation of the machine, showing parts in section, and illustrating the anvil lowered. Fig. 2, is a similar view, showing the anvil elevated so as to bring the same in proper position for use. Fig. 3, is a front edge view of the machine, showing the anvil elevated for use, and illustrating a section of work placed in proper position, and supported. 20 Fig. 4, is a horizontal section of the machine proper, showing a top view of a fence properly placed on supporting horses.

The present invention has relation to riveting machines designed and calculated for riveting fences or light structures, and it consists in the different parts and combination of parts hereinafter described and particularly pointed out in the claims.

Similar letters of reference indicate corresponding parts in all of the figures of the drawings.

In the accompanying drawings A, represents the body of the machine, which may be substantially of the form shown in the drawings, and should be formed of sufficient weight 35 to give the desired amount of strength and rigidity to the machine proper. The front or forward edge of the body A, is provided with the opening B, through which opening is 40 passed the bar or shaft a, which shaft is properly journaled in the body A.

To the bar or shaft a is securely attached in any convenient and well known manner, the L shaped foot lever C, which L shaped 45 foot lever is provided with the slotted arm D, which slotted arm engages the pin b, which pin is securely attached to the sliding block E, said sliding block being located upon the ledge F.

50 It will be understood that as the foot lever C is pressed or forced downward, the upper end of the slotted arm D, will be moved to-

ward the front edge of the body A, thereby carrying with it the block E.

The sliding block H is located substantially 55 as shown in Figs. 1 and 2, and as shown its bottom or lower end is provided with the right angled portion c, which right angled portion is provided with the inclined edge d, which inclined edge engages the inclined face 60 or edge d' formed upon the sliding block E, during the time the foot lever C is in the position illustrated in Fig. 1, thereby limiting the downward movement of the sliding block H.

To the top or upper end of the sliding block 65 H is attached the anvil I, which anvil moves up and down with the sliding block H. When it is desired to bring the anvil I into proper position for use, the foot lever C, is pressed downward, which movement elevates the sliding block H, by means of the inclined edges d, and d', and as the sliding block is carried under the bottom or lower end of the upper sliding block, said upper sliding block will 70 rest upon the lower sliding block, as illustrated in Fig. 2, thereby securely holding the anvil I, in proper position for use.

75 Directly above the anvil I, is located the reciprocating hammer J, which hammer is actuated by means of the housing K, the crank 80 e, and the springs f together with the collar g, rotary motion being communicated to the crank e, by means of the pulley g'. It will be understood, that in order to impart a true reciprocating movement to the hammer J, and 85 its different parts, that the crank e, must engage with a horizontal slot located in the housing K.

It will be understood that by providing the springs f, and locating them as shown that an 90 accelerating motion will be given to the hammer J. Upon the sides of the machine proper are located any desired number of horses or supports, such as L, to the top or upper ends of which are attached the adjustable bars h, 95 which adjustable bars carry the rollers k, said rollers being for the purpose of providing a means for easily moving the work through the machine proper, and under the hammer.

In use the work designed to be riveted is 100 placed in the machine proper, substantially as illustrated in Figs. 1 and 2, after which the rivet designed to be operated upon is placed in the position illustrated in Figs. 1 and 2,

and for the purpose of providing a means for easily entering the rivets in their proper places, the anvil I, is attached to the sliding head H, so that said anvil can be lowered so as to not interfere, or be in the way during the time a rivet is adjusted. After a rivet has been properly adjusted with reference to the hammer and anvil said anvil is elevated to the position illustrated in Fig. 2, which position supports the rivet, so that its top or upper end can be properly swaged or headed. After this operation is completed, the foot lever C is released, at which time said lever assumes the position illustrated in Fig 1, by reason of the counter-balances M, which counter-balances are attached to the arms a' said arms being securely attached to the shaft a.

It will also be understood, that by lowering the anvil I so as to clear the bottom or under side of the work, that the work can be moved back and forth, or slipped sidewise, without interfering, or coming in contact with the top or upper end of the anvil.

For the purpose of using various kinds of anvils for different grades of work, the anvil I, should be removably attached to the sliding block H.

Having fully described my invention, what

I claim as new, and desire to secure by Letters Patent, is—

1. In a riveting machine, the combination of a body provided with a vertically reciprocating hammer, and a vertically adjustable anvil, a foot lever provided with a slotted arm, a sliding block connected to the slotted arm, and provided with the inclined face or edge d', the sliding block H, provided with the right angled portion c, having the inclined edge d, and a counter-weight, substantially as and for the purpose specified.

2. In a riveting machine, the combination of a body provided with a reciprocating hammer, the sliding block H, provided with the anvil I and the right angled portion c, having the inclined edge d, the sliding block E, provided with the inclined face or edge d', the foot lever C, the slotted arm D, and a counter-balance, substantially as and for the purpose specified.

In testimony that I claim the above I have hereunto subscribed my name in the presence of two witnesses.

PAUL A. CUENOT.
